UNITED STATES PATENT OFFICE.

JAMES MARSHALL LEAVER, OF BAY MILLS, MICHIGAN, ASSIGNOR TO LEWIS A. HALL AND ROBERT H. MUNSON, OF SAME PLACE.

ART OF MANUFACTURING ARTICLES FROM PULP MATERIALS.

SPECIFICATION forming part of Letters Patent No. 660,644, dated October 30, 1900.

Application filed November 8, 1899. Serial No. 736,278. (No specimens.)

To all whom it may concern:

Be it known that I, JAMES MARSHALL LEAVER, a citizen of the United States, residing at Bay Mills, in the county of Chippewa and

5 State of Michigan, have invented a new and useful Art of Manufacturing Articles from Pulp Materials, of which the following is a specification.

This invention relates to the art of manufacturing articles from pulp materials, and has special reference to the manufacture of doors, shutters, sash, blinds, window-frames, door-frames, furniture, interior finish for houses, and other products or articles of a 15 like nature.

To this end the invention primarily contemplates a simple and efficient means for manufacturing in a cheap and practical manner articles from pulp materials which are 20 ordinarily constructed entirely of wood or of pulp and has specially in view the production of substantially solid articles or products in contradistinction to articles composed of sheets of pulp or sheets of pulp in combination with a wooden core, and in the construction of which articles the sheets, suitably embossed or ornamented, are attached to each other and also to the core. This construction of article is now known in the art; but 25

30 in the manufacture of sheets of pulp material considerable expense is necessarily involved, inasmuch as the sheets have to be prepared upon a plan analogous to that of paper-making, involving considerable labor 35 and complex machinery. The present invention obviates these objections to the manufacture of laminated sheet-pulp articles, while at the same time providing means for constructing a door, shutter, or analogous structure that will be entirely practical and durable and also susceptible to a wide range of ornamentation and decoration, which is only limited by the configuration of the dies and such foreign matter as may be mixed with 40 the pulp materials to produce any desired result.

With these objects in view the present invention primarily contemplates a novel process involving steps which provide for molding and pressing into shape articles from 45 pulp materials—such as doors, shutters, and

analogous structures—and at the same time baking the articles and imparting thereto any desired configuration or ornamentation in substantially a single operation.

55

While the fundamental features of the process are necessarily susceptible to modification and various forms of apparatus may be resorted to for carrying the process into effect without departing from the spirit or 60 principle thereof, still for illustrative purposes a preferable form of apparatus is shown in the accompanying drawings, in which—

Figure 1 is a plan view of the preferred form of apparatus utilized in carrying out 65 the invention. Fig. 2 is an end view thereof. Fig. 3 is a longitudinal sectional view on the line 3 3 of Fig. 1. Fig. 4 is a similar view on the line 4 4 of Fig. 1. Fig. 5 is a cross-sectional view on the line 5 5 of Fig. 1. Fig. 6 70 is a plan view, partly in section, of a door made from pulp materials illustrating a form of article that can be manufactured by the process. Fig. 7 is a plan view of the form of core which is utilized in constructing a door 75 from pulp materials. Fig. 8 is a cross-sectional view on the line 8 8 of Fig. 6.

Like numerals of reference designate corresponding parts in the several figures of the 80 drawings.

The present invention does not contemplate the formation of doors and analogous structures entirely from pulp material, as it is now common in different arts to mold articles from pulp; but in carrying out the process forming the subject-matter of the present application there is used in every instance a core of some description, which may be of any suitable material, but preferably of wood, on account of the strong adhesive contact that may 85 be secured between the same and the pulp material forming the main body and exterior portion of the article.

It will be understood that the invention is not limited to any specific article to be manufactured; but inasmuch as all articles made by the process have a suitable core to form a base or binder for the pulp material the nature of the invention will be fully understood by referring, for illustrative purposes, to a 90 door, made from pulp materials, manufactured in accordance with the invention. In 95

the construction of a door from pulp materials by means of the process the core 1 is of the same general configuration as the completed article, being of a rectangular form, as 5 shown in Fig. 7 of the drawings. The said rectangular core 1, though it may be of metal or other suitable material, is preferably constructed of wood, for the reasons explained, and is made in the form of a skeleton frame-work. Although in some forms of articles made from pulp materials and manufactured by the process the core may be solid or hollow and even imperforate, still in the construction of a door or analogous article with 10 a panel or panels it is necessary to provide the skeleton core 1 with panel-openings 2, which conform in size, shape, and disposition to the panel or panels of the completed article, and as these panel-openings entirely 15 pierce the core the same are completely filled by the pulp material, which is molded and pressed upon the core in a manner to be presently explained. By referring particularly to Fig. 8 of the drawings it will be observed 20 that the pulp material forming the body 3 of the door or like structure by being pressed upon the core from both sides thereof not only covers the side faces of the core, but the panel portions of the pulp material completely fill 25 the panel opening or openings of the core and produce a solid homogeneous mass of material in said opening or openings, thus producing a practically solid structure having 30 exceptional strength and durability.

35 From the foregoing it will be understood that it is essential in the formation of articles from pulp materials by the herein-described process that a suitable interior core be used to form a base or binder upon which the 40 pulp material may be pressed, and though different forms of apparatus may be utilized to carry the process into effect a preferred form is shown in the drawings, to which specific reference will now be made. In the preferred form of apparatus mentioned the same 45 includes a mold-box 4, which is preferably of a shape conforming to the outlines of the article to be manufactured therein; but ordinarily the said mold-box is of a rectangular 50 shape and essentially consists of a bottom or base 5 and the side and end walls 6 and 7, respectively, arising from the said bottom or base 5. The side and end walls 6 and 7 of the mold-box are rigidly joined together at their 55 contiguous edges by the corner-posts 8, which are fastened to the side and end walls by bolts or other suitable fastenings to form therein, in connection with the bottom or base 5, a substantially tight box structure, which is 60 designed to receive therein not only the pulp material and the core of the article, but also the instrumentalities which provide for molding, pressing, and baking the article, so that when the same is removed from the box it is 65 in a practically-finished condition.

The mold-box 4, as already explained, may be of any suitable shape, though the same is

preferably of a rectangular form and open at the top to admit of the escape of heat, vapor, and any waste product which may result from 70 the baking of the pulp material within the top portion of the box; but in carrying out the invention the end walls 7 of the mold-box are preferably constructed with access-openings 9, which are adapted to be covered and 75 uncovered by swinging end doors 10. Each end door 10 when swung into the opening with which it is associated entirely closes that end of the mold-box. To provide for the swinging support of the end doors, each 80 of the same is provided near one edge and at the upper and lower corners thereof with pindle-studs 11, journaled in suitable bearings 12, formed in the upper and lower sills of the end walls, and at its free unpivoted 85 edge each door is provided with a plurality of offstanding bifurcated lugs 13, adapted to be engaged and disengaged by the swing-bolts 14, fitted to and carried by a rock-shaft 15, journaled in suitable bearings at one 90 edge of the access-opening 9. When one of the end doors 10 is closed, it is simply necessary to move the adjacent swing-bolts 14 into engagement with the lugs 13 thereof and to tighten said bolts to provide for securely 95 fastening the door in its closed position. A loosening of the bolts and the swinging of the same away from the adjacent edge of the door will permit of the ready opening thereof to provide for either the insertion of the core 100 of the article or the removal of the completed article. It will be observed that by reason of this construction of the mold-box with swinging end doors fitted to the opposite end 105 walls thereof simple and efficient means are provided whereby ready access may be had to the interior working space of the mold-box through the ends thereof, thus greatly facilitating the handling of the core and the removal of the completed article. 110

The open-top-mold-box, constructed as described, is of a sufficient size to receive therein a pair of movable platens 16. These platens conform to the interior shape of the mold-box, the same extending the full length thereof from end to end and being of a width substantially equaling the depth of the box. The said platens are arranged in parallelism to form therebetween a working-space 17, and each of the same is of a hollow formation, 115 being provided therein with a plurality of separate and independent heating-chambers 18, 19, 20, 21, and 22, respectively. In the form of the apparatus shown in the drawings particular reference being made to Fig. 4, 120 the separate and independent heating-chambers extend longitudinally from end to end of the platen and are arranged closely together, though not in communication, to provide for the heating of the entire surface of 125 the platen which comes in contact with the pulp material within the working-space 17 of the mold-box. Each of the several heating-chambers of each platen 16 has a separate 130

and independent flexible pipe connection 23 with a common supply-pipe 24 for the heating agent, which may be steam, hot air, or hot water, as may be found the most suitable 5 for the purpose, according to the nature and composition of the pulp material that may be used in the construction of the article, and each of the flexible pipe connections, which may be properly termed "distributing-pipes" for the heating agent, is fitted with a controlling-valve 25, which provides means whereby each heating-chamber of the platen may have the heating agent supplied thereto or cut off therefrom independently of the remaining chambers. In addition to the individual supply-pipe connections for the several heating-chambers of each platen such chambers have also connected therewith, preferably at the ends thereof, separate and independent flexible drain-pipe connections 26, leading to the main drain-pipes 27, arranged exterior to the mold-box and providing in connection with the flexible pipes 26 means for draining off from the chambers of the 25 platens such condensed products or waste material as may result from the heating step.

The movable platens 16 in addition to the heating-chambers thereof are each preferably provided at their ends contiguous to the end 30 walls of the mold-box with packing-strips 28, loosely fitted to the platens in any suitable manner and yieldingly projected beyond the ends thereof by springs 29 or equivalent devices, which provide means for holding the 35 packing-strips yieldingly in contact with the end walls or doors of the mold-box to provide for closing the interstices at this point to prevent leakage of the pulp material while at the same time allowing for the contraction and expansion of the platens without interfering with their proper movement toward and away from each other in the operation of the apparatus. The said platens, which are designed to move toward and 40 away from each other, have fitted upon their opposing faces suitable dies 30. These dies may be held to the platens by holding-clips or any suitable means which permit of their ready attachment and removal, and the same 45 are of any desired configuration or design which is to be impressed upon the pulp material. In the construction of doors or analogous structures with a panel or panels the projecting portions of the dies are designed 50 to work into the panel opening or openings of the core and not only press the pulp material through said opening or openings in a solid homogeneous mass, but at the same time impressing upon the pulp material the 55 design or ornamental beading with which such articles are usually provided.

The core 1 of the article which is inserted into the working space 17 between the two platens through the access-opening at either 60 end of the mold-box is designed to be sustained in an upright position between and parallel with the platens, preferably by means

of the centering-screws 31, mounted in the end doors 10 of the mold-box and preferably provided with inner pointed ends 32, adapted to engage with the ends of the core, and thereby hold it in proper position to permit the pulp material to be pressed and molded into shape thereon.

In the operation of the apparatus it will be 75 necessary to provide for the movement of the platens toward and away from each other, and to secure this movement in a positive manner there are employed pairs of operating-screws 33, arranged, respectively, above 80 and below the platens at the top and bottom of the mold-box, as plainly shown in Figs. 4 and 5 of the drawings. The pairs of operating-screws 33 are swiveled or journaled at opposite sides of the mold-box in suitable bearings 34 and are also provided with separate right and left threaded portions 35, which work in the threaded openings 35^a, formed in the extremities of the upright carrier-bars 35^b, to which the platens are suitably fastened, so 90 as to be carried thereby. The operating-screws 33 are extended beyond one side of the mold-box and are designed to be associated with gearing or any other suitable operating means to provide for turning the same either 95 backward or forward, according to the desired movement to be imparted to the movable platens, and at this point it will be observed that by reason of attaching the platens to the carrier-bars 35^b, which project above 100 and below the same, there is no interference whatever with the action of the platens upon the material, and the necessity of piercing the platens with threaded openings for the reception of the screws is obviated.

When the screws 33 are turned in one direction, the movable platens 16 will be caused to approach each other, while the turning of the screws in the opposite direction will cause the platens of each pair to recede from each other and away from the article formed therebetween, and it may be observed at this point that the platens may be caused to move at any rate of speed that may be desired and the operation may be stopped during any step of 110 the process and again resumed, as experience and the nature of the material may require. It will further be observed that in the preferable construction of the apparatus the inner faces of the end doors and the bottom of the 115 mold-box are planed perfectly true to prevent leakage, the packing-strips 28, already referred to, assisting in securing this desirable result.

In constructing the apparatus it is also desirable to provide means for allowing heat, vapor, and waste material to escape from the edges of the article during the baking thereof. To make provision for this, the bottom or base 5 of the mold-box is provided in the 120 upper side thereof with a longitudinal waste channel or gutter 37, extending from end to end of the bottom and declining toward both ends thereof, so that any waste product or ma-

terial entering the same may be readily discharged at the ends of the mold-box. The said longitudinal waste channel or gutter 37 is arranged in such a position as to be disposed 5 at the bottom of the working space 17, and at its upper open side the said channel or gutter 37 is preferably covered by a perforate cover-plate 38, formed of perforated metal, wire-gauze, or equivalent material. In addition 10 to providing the bottom of the mold-box with the waste channel or gutter 37 the end doors or walls thereof are also provided in their inner faces with longitudinally-disposed waste channels or gutters 39, which are covered by 15 perforate cover-plates 40, similar to the perforate cover-plate 38, and which when the doors are closed communicate with the bottom waste channel or gutter 37, and thereby provide for the complete removal of such 20 waste products or materials as may escape from the edges of the article during the baking process.

In carrying out the process the pulp material used may be wood-pulp material, paper-pulp material, or in fact any pulp material that can be utilized for the purpose, and prior to introducing this pulp material into the mold-box such coloring or adhesive ingredients as it may be desired to use are mixed 25 therewith. With reference to the use of the adhesive compound it may be explained at this point that when the same is incorporated into the pulp material it subserves two important functions—first, to cause the material 30 to attach itself more firmly to the core, and, second, to cement the particles of the pulp material firmly together into a homogeneous mass while at the same time imparting smoothness and finish to that part of the pulp material contacting with the faces of the dies. Instead of introducing the adhesive compound or substance directly into the pulp material the same may be applied directly to the core itself prior to the application of the pulp 35 thereto to insure a firmer adherence of the pulp material to the core, and while either of these methods of using the adhesive compound or substance may be resorted to it will be understood that if found expedient or desirable both methods may be utilized at once—namely, to introduce the adhesive compound or substance into the pulp material and also to apply the same directly to the core prior to the application of the pulp material. 40

55 After having prepared the pulp material the core, which is inserted through one of the end access-openings and supported in place by the centering-screws 31, is completely enveloped with the pulp material, so that the 60 same will fill any interstices or openings with which it may be provided. With the core in position and enveloped by the pulp material heat may be applied to all of the heating-chambers of the platens at one time or to 65 such chambers as may be considered desirable; but a preferable way of carrying out the process is to first admit the heating agent

to such heating-chambers of each platen through the distributing-pipe connections as are in closest proximity to the densest portions of the pulp materials. This will result in warming up the thickest portions of the pulp materials first, causing the vapor and waste products to work out of the same toward the edges. By then applying the heating agent to the adjoining chambers the vapor and waste products will be still more worked out toward the edges of the article, so that when the heating agent is finally admitted to the uppermost and lowermost heating-chambers of the platens the baking of the article will be thoroughly accomplished. By reason of this operation uneven baking of the material may be obviated and a practically-uniform result obtained, which is very desirable 85 in the construction of such articles as doors and the like. In other words, it is preferable in carrying out the invention to successively apply the heat from the central portion of the article out toward the edges thereof to insure a thorough drying and baking of the same, and in the manufacture of doors and like articles this method of heating will provide for warming up the densest or thickest 90 portions of the pulp material first. 95

While heat is applied to the platens through the medium of the heating-chambers and pipe connections described, the adhesive compound added to the pulp material is caused to fuse and harden and the vapor and waste products pass out through the open top of the box, while vapor and other waste products are also permitted to readily escape into the channels 37 and 39. During the baking of the pulp material motion is imparted 100 to the movable platens, which are caused to approach each other gradually until the vapor and waste products have been thoroughly eliminated and the resultant mass is completely baked, and consists of the interior 105 core 1 and the homogeneous body 3, entirely surrounding the same and completely filling any interstices or openings thereof. At the time the platen presses the pulp material upon its core the die-faces or dies 30 thereof 110 will impress upon the surfaces of the pulp material any desired design or ornamentation. When the article has thus been completed, the movable platens are caused to recede from the same, so that the article can 115 be readily removed through either end door. 120

In connection with the construction described it will be observed that the provision of the waste-channels greatly shortens the operation of baking. 125

After removing the completed article from the mold-box if a higher degree of finish is desired than may be obtained in the process just described the article may be placed in any ordinary stamping-press with dies and 130 by the action of pressure or heat, or both, may be given a still more attractive and durable finish. The article of course is also susceptible to decoration or embellishment

by paints, stains, varnishes, or other well-known means.

From the foregoing it is thought that the essential steps of the herein-described process will be readily understood by those skilled in the art without further description, and it will be understood that any changes which do not affect the result accomplished by these steps may be resorted to without departing from the spirit or sacrificing any of the advantages of the invention.

The apparatus described herein forms no part of the present application, as the same constitutes the subject-matter of my companion application, Serial No. 736,277, patented August 28, 1900, No. 656,742.

Having thus described the invention, what is claimed as new, and desired to be secured by Letters Patent, is—

1. A process for making articles having a permanent interior core having openings and a body portion of pulp material, the same consisting in applying pressure of the same degree simultaneously to opposite sides of the pulp material, and forcing the opposite portions thereof into homogeneous union through the openings in the core and also upon the faces of the same, subjecting the pulp material to heat during the application of the pressure, and molding surface ornamentation upon both faces of the article simultaneously with the application of the heat and pressure.

2. A process for making articles from pulp materials having thinner and denser portions which consists in applying pressure to the body of material to form the said article, and simultaneously applying heat successively from the denser to the thinner portions thereof.

3. A process for making articles having a permanent interior core and a body portion of pulp material having thinner and denser portions, the same consisting in simultaneously applying pressure of the same degree to opposite sides of the material to form the said article, successively applying heat from the denser to the thinner portions of the material, and molding and pressing the material upon its core during the successive application of the heat.

4. A process for making articles having a permanent interior core and a body portion of pulp material, the same consisting in applying pressure of the same degree simultaneously to opposite sides of the pulp material and forcing the opposite portions thereof compactly upon the faces of the core causing a positive and permanent adhesion of the pulp material to the core, subjecting the pulp material to heat during the application of the pressure, and molding surface ornamentation upon both faces of the article simultaneously with the application of the heat and pressure.

5. A process for making articles having a permanent interior core and a body portion of pulp material adhesively united thereto, the same consisting in applying pressure to the body of pulp material to press the same upon the core, and simultaneously applying heat successively from the central portion of the article toward the edges thereof.

In testimony that I claim the foregoing as my own I have hereto affixed my signature in the presence of two witnesses.

JAMES MARSHALL LEAVER.
